UNITED STATES PATENT OFFICE.

EMIL GATHMANN, OF WASHINGTON, DISTRICT OF COLUMBIA, ASSIGNOR
TO GEORGE WHITMAN McMULLEN, OF PICTON, ONTARIO, CANADA.

APPARATUS FOR DRYING POWDER RODS.

SPECIFICATION forming part of Letters Patent No. 777,504, dated December 13, 1904.

Application filed June 19, 1901. Serial No. 65,199. (No model.)

To all whom it may concern:

Be it known that I, EMIL GATHMANN, of Washington, District of Columbia, have invented certain new and useful Improvements 5 in Apparatus for Drying Powder Rods, of which the following is a specification.

This invention relates to improvements in apparatus for drying powder rods, and thereby volatilizing and expelling solvent therefrom; and the invention refers more specifically to an improved drying-chamber adapted to be exhausted artificially and provided interiorly with skeleton supports whereby the commodity being acted upon is confined and 15 supported during the drying operation.

The object of the invention is to provide a simple, effective, and cheap apparatus of the character referred to which will serve to rapidly dry the powder rods placed therein and 20 at the same time so confine and support the rods as to insure their retention in proper shape.

The invention consists in the matter hereinafter described, and more particularly pointed out in the appended claims, and the same will be readily understood from the following description, reference being had to the accompanying drawings, wherein—

Figure 1 is a side elevation of the preferred 30 embodiment of my invention, parts being broken away to expose the internal construction. Fig. 2 is a top plan view of the same with parts broken away to expose the internal arrangement. Fig. 3 is a fragmentary 35 detail, in perspective view, of a modified form of support adapted for use in connection with other features of my invention. Fig. 4 is a fragmentary plan view of still another modified form of skeleton support. Fig. 5 is a 40 sectional view of the support shown in Fig. 4. Fig. 6 is a fragmentary sectional view of a series of supports, similar to those shown in Figs. 4 and 5, with powder-rods arranged therein, showing the relative arrangement of 45 the several parts; and Figs. 7 and 8 are views similar to Figs. 4 and 5, respectively, of still another modification.

In drying smokeless colloid powders it is

desirable to remove the volatile solvent which is used in the compound of the nitrocellulose 50 artificially or more rapidly than the solvent would be dried out by simple exposure to the atmosphere. The green grains or rods of powder are therefore placed in a hermetically-sealed receptacle or tank and a current of 55 heated air is passed through the same, preferably an induced current caused by a suction-pump, so as to create a partial vacuum in a receptacle, and thus more readily and effectually withdraw the solvent from the powder rods or grains. The volatilized solvent thus carried off from the powder is passed through a condenser and after suitable treatment is again ready for use in the further 60 making of powder.

The recovery of the solvent withdrawn from the powder during the drying of the latter is quite essential in the economical manufacture of powder, since without a suitable recovery apparatus the solvent would be lost by evaporation or dispersion, whereas with a suitable closed apparatus, such as hereinafter described, a given quantity of solvent will serve 65 to treat a maximum amount of powder.

It is not to be understood from the foregoing, however, that I claim as broadly new the idea of thus drying the powder in a closed chamber and recovering the volatilized solvent, the foregoing description of a process 70 being given for the purpose of a more clear 80 comprehension of the present invention, which refers solely to an apparatus adapted for carrying out such a process.

The apparatus hereinafter described is particularly well adapted to the treatment of colloid powder which is shaped or formed in rods or strips—such, for example, as that shown in my Letters Patent No. 660,567—and it is to be noted in this connection that all colloid powders with which I am familiar, and especially the pyroxylin varieties, undergo great shrinkage during their transformation from the original or green state to a dried condition. During this shrinkage of the powder considerable warpage or distortion in shape 90 will occur, this being particularly true if the 95

powder is in the form of rods or strips of any considerable length, unless means be provided for positively preventing such distortion.

Referring now to the drawings, 1 designates 5 as a whole a closed tank or drying-chamber, which can be made of any suitable material, preferably metal, a desirable form being that shown in the drawings, wherein the tank is shown as an oblong rectangular box having the 10 entire end walls 2' made movable. In the preferred embodiment shown the side walls of the tank are of sheet metal reinforced around the end margins thereof by means of ribs 3, which project slightly beyond the ends of the 15 side wall proper of the tank and are made knife-edged, so as to sink slightly into packing-rings 4, inserted in the meeting faces of the end covers or walls 2, and thus effect a more certain hermetical joint and at the same time 20 leave an air-space at each end which is not interrupted by the skeleton partitions herein-after referred to. Suitable pivot-ears 3' are provided upon the reinforcing-rings 3, with which are pivotally engaged threaded clamping-bolts 5, which are adapted to extend 25 between pairs of clamping-ears 2', formed upon the cover members, thumb-nuts 5' being threaded upon the ends of the clamping-bolts to engage the clamping-ears, and thus draw 30 the end covers into compressed engagement with the tank-body proper. Preferably in order to withstand this clamping pressure said end walls are made in the form of castings, and each is provided with a suitable aperture 35 within which are seated pipes 6 and 7, respectively, one of which serves as an inlet and the other as an eduction pipe. The interior of the hermetical chamber thus formed is divided by means of a series of skeleton 40 partitions into a plurality of straight tubular passages (designated 8' in the respective figures of the drawings) adapted to receive the powder rods placed endwise therein. It will be understood that the shape of these tubular 45 passages in cross-section will be varied to approximately conform to the shape of the particular powder rod to be treated, the passages in the form of skeleton support shown in Figs. 1 and 2 being adapted to contain cylindric rods 50 and being therefore approximately circular.

In the preferred embodiment shown in Figs. 1 and 2 the skeleton supports are formed by means of a series of corrugated plates 8, arranged side by side to extend throughout 55 the full length of the tank and in such relation to each other as to provide the intervening circular spaces or passages 8', hereinbefore referred to. In order to provide for a free circulation throughout the entire interior 60 of the chamber, these corrugated plates 8 are perforated or made of foraminated form. The powder rods are placed endwise within these several tubular passages, as indicated at 9, Figs. 1 and 2, and are obviously thereby supported and confined against warping to any 65

considerable extent regardless of what position the tank be placed in. At the same time a free and thorough circulation may take place throughout the entire interior of the tank, so that the powder rods will be dried 70 rapidly and uniformly by the circulation therethrough of a current of warm air.

In Fig. 3 I have shown a modification in which the skeleton supports are formed by means of strips or slats 11 arranged in intersecting relation and notched together, as indicated at 12 and 13, in a familiar manner, so as to form rectangular passages 10. A series of these skeleton supports will be arranged at intervals apart in parallel relation to each 80 other and with their several passages 10 in alignment throughout the length of the tank—for example, in substantially the relation shown in Fig. 6. A tank equipped with skeleton supports of this construction is suitable 85 for drying powder rods approximately rectangular in cross-section, and the intervals between the several supports obviously afford the necessary free circulation throughout the tank. 90

In Figs. 4, 5, and 6 I have shown a modification in which the skeleton supports 14 are made from sheet metal perforated at intervals apart to form the passages 8', the margin of each perforation or passage being surrounded by an annular flange 16, struck up by means of suitable dies. The arrangement of skeleton supports of this construction is substantially that described in connection with Fig. 3 and is clearly shown in Fig. 6, wherein 100 a couple of powder rods 9 are shown as placed in position. 95

In Figs. 7 and 8 I have shown still another modification, which is substantially the same as that shown in Figs. 4, 5, and 6, the only 105 difference being that the passages 8', formed through the supports 17, are made of oblong rectangular shape in plan, such a construction being suitable for supporting and confining powder rods made in the form of strips conforming in cross-section approximately to the shape of the passages 8' of this modification. 110

The use of the apparatus has been indicated in connection with the foregoing description, 115 but may be again briefly referred to. One or both of the end walls of the chamber having been removed, the green powder rods are adjusted into the several tubular passages, the end walls returned to place, and the inlet and eduction pipes respectively connected with a source of warm air and with an exhaust mechanism or pump leading to a condensing apparatus. The pump is then operated and the current of air passed through the chamber 120 until the powder rods have been completely dried, it being noted that it is desirable that the inlet should be so controlled and the pump so operated as to create a partial vacuum 125 within the chamber, thereby greatly facilitat- 130

ing the evaporation of the solvent contained in the powder rods.

By isolating the powder rods or strips in the manner described the warping or deforming of the rods is prevented, inasmuch as each rod is properly inclosed throughout its length in an envelop, to which it must conform in shape while drying.

The time of drying or removing of the solvent is greatly shortened when the powder elements or rods are thus kept separate from one another and the solvent is more thoroughly removed from the powder. This is due to a more thorough circulation of the heated air-current.

While, as hereinbefore indicated, I have shown what I deem to be a preferred embodiment of my invention, yet it will be obvious that the details thereof may be still further modified without departing from the spirit of the invention, and I do not, therefore, wish to be limited to the details of construction shown except to the extent that the same are made the subject of specific claims.

25 I claim as my invention—

1. A powder-drying receptacle comprising a hermetically-sealed chamber and holders or supports arranged therein to divide the interior into long straight passages opening into a common air-space at each end, which passages are adapted to receive powder rods and to confine the same against warping, for the purpose set forth.

2. A powder-drying receptacle comprising a closed chamber, a series of skeleton supports arranged therein to divide the interior into parallel elongated passages, and eduction and inlet passages arranged to communicate with said chamber at separate points.

40 3. A powder-drying receptacle comprising a hermetically-closed chamber, means for confining against warping and supporting a plu-

rality of series of powder elements in position individually separated from each other within said chamber and inlet and eduction pipes 45 communicating with said chamber at separated points and opening respectively into common air-spaces at the ends of said receptacle, for the purpose set forth.

4. A powder-drying receptacle comprising 50 a closed chamber having a removable wall-section forming a hermetically-sealing closure, a series of skeleton supports arranged within the chamber to divide the interior thereof into long narrow passages accessible 55 for the insertion of powder rods or the like when the closure is removed, and eduction and inlet pipes communicating with said chamber at opposite ends of said tubular passage.

5. A powder-drying receptacle comprising 60 a chamber provided with a hermetically-sealing removable closure, a series of corrugated and perforated plates arranged therein to form a series of separate, long and relatively narrow passages and inlet and outlet eduction pipes 65 communicating with said chamber at separate points.

6. A powder-drying receptacle comprising an elongated tank-body of substantially uniform size throughout its length and provided 70 with hermetically-sealing removable end walls, clamping devices for holding said end walls removably in position, inlet and eduction pipes communicating with the interior of the tank at opposite sides thereof and a series of 75 similarly-corrugated plates arranged continuously and dividing the interior thereof into elongated passages extending longitudinally of the tank, substantially as described.

EMIL GATHMANN.
